UNITED STATES PATENT OFFICE.

OBERT C. YSTENESS, OF BEJOU, MINNESOTA.

WHIFFLETREE HOOK.

Application filed November 13, 1923. Serial No. 674,518.

To all whom it may concern:

Be it known that I, OBERT C. YSTENESS, a citizen of the United States, residing in Bejou, State of Minnesota, have invented 5 certain new and useful Improvements in Whiffletree Hooks, of which the following is a specification.

This invention relates to whiffletree hooks, and has for its primary object the provision, 10 in a manner as hereinafter set forth, of a hook so constructed that the eye of the tug strap when placed thereupon may be secured against displacement when the tug strap becomes flat.

15 A further object of the invention is the provision, in a manner as hereinafter set forth, of a whiffletree hook having swinging means for locking the eye of the tug strap thereon and further so constructed 20 that when the tug strap eye is put under strain, the entire pressure will be put upon the hook and no strain will be put upon the lock portion.

25 A further object of the invention is the provision, in a manner as hereinafter set forth, of a whiffletree hook having its free end extending inwardly at a slight curve to provide a guide for the tug strap eye, to 30 expedite the application of the eye to the hook.

The final object of the invention is the provision, in manner as hereinafter set forth, of a whiffletree hook of simple structure, few parts, strong, durable and inexpensive to manufacture.

35 The invention will be best understood from a consideration of the following detailed description taken in connection with the accompanying drawings forming part 40 of this specification, with the understanding that the invention is not confined to any strict conformity with the showing of the drawings, but may be changed and modified so long as such changes and modifications 45 mark no material departure from the salient features of the invention as expressed in the appended claims.

In the drawings:—

50 Figure 1 is a top plan view of the device embodying this invention, being shown as applied to one end of the whiffletree.

Fig. 2 is a sectional view taken on the line 2—2 of Fig. 1.

Fig. 3 is a detail view partly in section,

showing the position occupied by the lug 55 eye, when it is desired to open the hook and remove the eye therefrom.

Fig. 4 is a perspective view of the device embodying this invention, showing a different method of application to the whiffletree, 60 than the method disclosed in Fig. 1.

Referring now to the drawings in detail wherein like numerals of reference indicate corresponding parts throughout the several figures of the drawing, numeral 1 indicates 65 one end of the whiffletree, to the forward face of which the device embodying the present invention is secured. This device comprises a substantially L-shaped bar 2 having the lower flanged portion 3 extending forwardly of the whiffletree body thus bringing the back of the upright portion against the surface of the whiffletree. This vertical portion 2 has provided therein passages for the insertion of bolts 4 by which the device 70 is secured to the whiffletree. It is of course understood that other means may be employed for securing the device to the whiffletree, and as shown in Figure 4 of the drawings, a ferrule 5 is provided which surrounds the end of the whiffletree and through which the bolts 6 pass to secure the ferrule in position. Two forms have been shown for securing the device to the whiffletree, but it is of course to be understood that 75 any appropriate means may be made use of. The following description of the device will 80 be confined to the showing of Figure 1 and its related figures in order that the specification may read clearly.

90 The hook comprises a U-shaped body portion 8 having the shank 7 formed integrally with the outer portion of the whiffletree connection 2, and where it connects with the connection 2, it is of the same width as the 95 connection. This shank extends forwardly a short distance when it is cut downwardly from its upper edge at an angle to provide a sloping portion 9, the lower end of which sloping portion terminates in a vertical portion 10 which merges into the body of the hook 8. The under portion of the hook, as clearly shown in Fig. 3, is very nearly in the same plane with the bottom of the flange 3. The inner or free end of the hook 8 is 100 extended, into a substantially elongated slightly inwardly bowed tongue 11. This tongue 11 is positioned forwardly of the 105

flange 3 in substantially parallel relation thereto, a sufficient distance to allow the passage of the tug strap eye indicated at 12, thereover, without binding between the two parts.

Means is provided for locking the tug strap eye 12 upon the hook 8, in the form of a flat U-shaped hook member 13, the free end 14 of which is upon the side of the hook 8 opposite to its tongue 11, this hook 13 being formed flat to lie upon the flat surface of the hook 8, and when positioned thereupon the end 14 lies adjacent the vertical wall 10 of the hook 8. The hook 13 has a shank member 15 which extends inwardly across the inside of the hook to a point in line with the central part of the free end 14, whereupon the shank is bent rearwardly at right angles to the body portion 15 to provide the flat bearing member 16 which bears against and is bolted to the inner surface of the shank 7 of the hook 8, by means of a bolt or rivet 17.

As clearly shown in Figure 1, the crotch 18 of the hook 13 is cut deeper than the crotch of the hook 8, and when the tug strap eye 12 is in position, it does not touch the crotch 18 of the hook 13, but bears only against the hook 8. The hook 13 is also made of sufficient length to overlap the hook 8 when the two hooks are brought together; this overlapped portion indicated at 19, serving as a grasping tab to lift the hook 13 from the hook 8.

When it is desired to remove the tug strap eye from the hook, it is necessary that the eye be swung outward toward the outer end of the whiffletree and then swung upwardly and laid back upon the sloping portion 9 of the shank of the hook 8, as shown in Figure 3. In this position, the hook 13 may be

raised and passes easily over the eye 12, whereupon the eye 12 is swung outwardly and downwardly and then in and across the tongue 11 of the hook 8, to be removed. 45

What I claim is:—

1. A whiffletree hook comprising, a U-shaped body portion having one end of greater length than the other, an angularly disposed attaching means extending from 50 said long end, a guide tongue extending at an angle from the other end and substantially in parallel relation to the attaching means, and closure means for said body portion comprising a hook having one end pivotally secured to said long end upon its inner side and adapted to rest upon said body portion when in engaged position, said closure hook having its crotch cut deeper than the crotch of said body portion to avoid contact with an engaging member, and further having its outer portion extended beyond said body portion to provide a finger engaging tab. 55

2. A whiffletree hook comprising, a U- 65 shaped body portion having one end of greater length than the other, an angularly disposed attaching means extending from said long end, a guide tongue extending at an angle from the other end and substantially in parallel relation to the attaching means, a closure means for said body portion comprising a substantially U-shaped hook member having one end turned inwardly to extend across the body of the 70 hook and pivotally secured to said long end upon its inner side, said hook member being adapted to rest upon said body portion when in engaged position. 75

In testimony whereof, I affix my signature 80 hereto.

OBERT C. YSTENESS.
